FIREPLACE GRATE

Albert Cliffe Arrand, 196 Jenkins Road, Andover, Mass.

Filed May 20, 1959, Ser. No. 55,988

Term of patent 14 years

(Cl. D81—18)

Fig. 1 is a perspective view of the fireplace grate of the invention.

Fig. 2 is a section taken on line 2—2 of Fig. 1.

Fig. 3 is a side perspective view thereof, it being understood that the perforations are continuous throughout as shown in Fig. 1.

I claim:

The ornamental design for a fireplace grate, as shown.
